F. B. LITTLE.
ELECTROMECHANICAL ACTION FOR MUSICAL INSTRUMENTS.
APPLICATION FILED FEB. 25, 1916.

1,228,223.

Patented May 29, 1917.

Inventor:
Frederick B. Little.
By G. L. Gramitto.

UNITED STATES PATENT OFFICE.

FREDERICK B. LITTLE, OF CHICAGO, ILLINOIS, ASSIGNOR, BY MESNE ASSIGNMENTS, TO
J. C. DEAGAN MUSICAL BELLS, OF CHICAGO, ILLINOIS, A CORPORATION OF ILLINOIS.

ELECTROMECHANICAL ACTION FOR MUSICAL INSTRUMENTS.

1,228,223.

Specification of Letters Patent.

Patented May 29, 1917.

Application filed February 25, 1916. Serial No. 80,328.

To all whom it may concern:

Be it known that I, FREDERICK B. LITTLE, citizen of the United States, residing at Chicago, in the county of Cook and State of Illinois, have invented a certain new and useful Improvement in Electromechanical Actions for Musical Instruments, of which the following is a full, clear, concise, and exact description, reference being had to the accompanying drawings, forming a part of this specification.

My invention relates to musical instruments of the percussion type and has for its object the construction of an improved electro-magnetic action whereby the sound producing elements of the instrument may be impinged upon by hammers with blows of suitable force and in such manner that the hammers will not dampen the vibrations they set up in the sound producing elements. In practising my invention I employ an electro-magnet for each action, the armature of the magnet carrying a hammer and also a switch actuating element for opening the circuit of the magnet when the hammer has been moved a predetermined distance toward the sound producing element it is to strike whereby the circuit of the magnet is opened before the hammer completes its travel, momentum being relied upon to complete the hammer travel. A spring is employed against the force of which the magnet moves the hammer and against the force of which the hammer is moved by momentum when the circuit of the magnet is opened, the spring serving to restore the hammer after it has struck so that the hammer will not linger to dampen the vibrations set up in the vibrating element it has struck. I will explain my invention fully by reference to the accompanying drawing showing the preferred embodiment thereof and in which Figure 1 is a view taken generally on line 1 1 of Fig. 2, the circuit arrangement of the magnet being also diagrammatically indicated in this figure; Fig. 2 is a front view of the structure shown in Fig. 1, a cap being shown in section at the upper end of the figure to reveal parts that it would hide; Fig. 3 is a perspective view of the switching and armature mechanism which I prefer to employ; Fig. 4 is an end elevation of the magnet structure shown in Figs. 1 and 2, the hammer being removed while the casing is shown in cross section on

line 4 4 of Fig. 1; and Fig. 5 is a view taken at right angles to the part shown in Fig. 4.

Like parts are indicated by similar characters of reference throughout the different figures.

The sound producing elements to which my invention is adapted may be of any suitable nature, the sound producing element illustrated in the drawing being in the form of a vibrating bar 1 located in front of a resonator 2 as will be well understood by those familiar with the art. A hammer 3 for striking the bar 1 is pivotally mounted at 4 to and between the ears 5 projecting from a bracket 6 that is attached to the cylindrical casing 7 by the screws 8. Nuts 9 are threaded upon the free ends of the hammer stem 10, the hammer ball 3 being secured between the nuts and being adjustable longitudinally of the stem by reason thereof. The other end of the hammer stem projects from the armature 11, which is preferably circular, that carries the bar 12 by means of which the armature, as well as the hammer, is pivoted at 4. The bracket 6 carries an arm 13 that is insulated therefrom, a screw 14 having threaded connection with this arm. A binding nut 15 is provided upon the screw for the purpose of engaging a circuit terminal therebetween and the bar 13 whereby the screw is brought into electrical connection with such terminal. A terminal contact 16 is carried by the screw 14, this contact being complementary to a terminal contact 17 carried upon one end of the leaf spring 18 whose other end is secured to a rigid arm 19 that is rigidly assembled with the bracket 6 by means of the bolt 20 and the nut engaging the same. The arm 19, obviously, is insulated from the arm 13 since the latter arm is insulated from the bracket 6. The arm 19, however, may be electrically connected with the bracket and the metallic parts upon the bracket. The magnet winding 21 of each action is included in a circuit traceable from the battery 22, the circuit closing instrument playing key 23, the contact screw 14 and the contact 16 carried upon one end thereof, the contact 17 and the leaf spring 18 carrying this contact, thence to the winding 21 back to the battery. Whenever the switch 23 is closed the winding 21 is energized and the armature 11 of the magnet is attracted to move the hammer to-

ward the sounding bar, the magnet being magnetically pulled until the insulating block 24 carried by the bight of the stirrup 25 engages the spring 18 that passes through the stirrup, it being observed that the stirrup moves with the armature as it is clamped between the armature and the bar 12. The engagement of the switch actuator 24 with the switch spring 18 occurs before the hammer 9 strikes the bar 1 and serves to break the circuit of the magnet at this time whereby the hammer completes its movement by momentum, it being thereby prevented from dampening the vibrations it sets up as it is instantly removed from engagement with the bar by the retractile spring 26. This spring not only serves to retract the armature and the hammer but also serves to dampen the movement of the armature when the armature is magnetically attracted whereby the momentum imparted to the hammer is properly reduced. The magnet winding 21 is set into an iron cup 21¹ that is provided to make the magnet ironclad. The iron core 27 is attached to the end wall of this cup. The armature at the other end of the cup-shaped casing is opposed to the core and the rim of the casing, the magnet structure illustrated being highly efficient as there are no wasteful air gaps to be threaded by magnetic flux. The spool upon which the winding is disposed is preferably made of brass, the core 27 passing through the spool sleeve 28 while the end walls 29 of the spool define the winding space. A piece of felt 30 may be provided to prevent the armature from sticking and to prevent it from making noise when the hammer strikes.

40 Each switch 23 is individual to one magnet, it being understood that the different magnets are associated with different sounding bars that are arranged to produce the sounds of a musical scale. Taps 31 indicate the conductors that lead from the battery 22 to other switches 23 and taps 32 indicate conductors that lead from the other side of battery 22 to other magnet windings 21, though other circuit arrangement may be employed. The battery itself is included in a conductor that is common to all of the magnets, this conductor also including a switch 33 which may be thrown into one position when all of the magnets are to be excluded from circuit, which may have an intermediate position when the normal battery 22 is to be included in circuit; and which may have a third position when the

extra battery 34 is to be included in series with the battery 22 to increase the voltage 60 and cause the stronger operation of the hammer, the switch 33 thus constituting a modulating switch as well as a circuit opening and closing switch.

The insulating block 24 is desirably made 65 of cushioning material and also extends outwardly so as to engage the arm acting as a rigid back stop when the armature is retracted, the contact actuator of which the insulating block 24 forms a part being also 70 employed as a means to limit the extent to which the armature may be retracted. The stirrup that supports the block is preferably resilient as well as the block 24 so that the armature is not violently arrested in its re- 75 storing movement.

While I have herein shown and particularly described the preferred embodiment of my invention I do not wish to be limited to the precise details of construction shown 80 as changes may readily be made without departing from the spirit of my invention, but having thus described my invention I claim as new and desire to secure by Letters Patent the following:—

85 An electro-mechanical action for percussion musical instruments including an electro-magnet; a hammer carried by the armature of the magnet; a pair of contacts in the magnet circuit, one of these contacts 90 having a spring support to enable it to be moved toward and from the other; a mounting for these contacts that is apart from the magnet armature; a contact actuator carried by the armature and arranged to move 95 said spring support to exclude the magnet from circuit before the magnetically attracted armature has completed its range of movement whereby the hammer will continue in movement of momentum; and a 100 spring for restoring the armature and hammer and against the force of which spring the armature is magnetically attracted, the aforesaid mounting constituting a back stop 105 engaged by said contact actuator when the armature is restored to limit the restoring movement of the armature effected by the armature restoring spring.

In witness whereof, I hereunto subscribe my name this 17th day of February A. D., 110 1916.

FREDERICK B. LITTLE.
